DOLL

Howard Landorf, New York, N. Y.

Application May 23, 1952, Serial No. 19,851

Term of patent 3½ years

(Cl. D34—4)

To all whom it may concern:

Be it known that I, Howard Landorf, a citizen of the United States, residing at New York, in the county of New York and State of New York, have invented a new, original, and ornamental Design for a Doll, of which the following is a specification, reference being had to the accompanying drawing, forming part thereof.

In the drawing:

Fig. 1 is a front elevational view of a doll, showing my new design; and

Fig. 2 is a rear elevational view of the same.

I claim:

The ornamental design for a doll, as shown.

HOWARD LANDORF.
